UNITED STATES PATENT OFFICE.

JOHN A. WALDBURGER AND WILLIAM J. SMITH, OF MCKEESPORT,
PENNSYLVANIA.

POWER APPARATUS FOR REMOVING SKULL FROM LADLES.

SPECIFICATION forming part of Letters Patent No. 663,946, dated December 18, 1900.

Application filed April 5, 1900. Serial No. 11,650. (No model.)

To all whom it may concern:

Be it known that we, JOHN A. WALDBURGER and WILLIAM J. SMITH, citizens of the United States, residing at McKeesport, in the county 5 of Allegheny and State of Pennsylvania, have invented or discovered new and useful Improvements in Power Apparatus for Removing Skull from Ladles, of which the following is a specification.

10 In the accompanying drawings, which make part of this specification, Figure I is a side elevation, partly in section, of our apparatus for removing skull from ladles. Fig. II is a similar view at right angles to the first, showing 15 the ram actually working. Fig. III shows the apparatus removing the skull while the ladle is mounted on a ladle-car.

The purposes of our invention, generally stated, are to devise simple and powerful 20 mechanism for removing skull from ladles without materially disturbing the lining of said ladle.

Our apparatus is adapted for use with all kinds of ladles from which the skull has to be 25 removed, although it is most satisfactory when employed with a ladle such as shown in an application executed on an even date here-with filed by us, Serial No. 11,649, which ladle has a ring of metallic lining at the top 30 portion thereof; but we do not restrict the claims of the present application to use with such ladle. The molten iron adheres to the same in the form of skull, and more particularly at or near the line of the level of the 35 liquid and also at the bottom of the ladle. The usual way of removing skull is to tip the ladle violently and jar the skull out. If this is not successful, the skull must be removed by hammering it clear. This dislodgment of 40 the skull in the manner just described involves frequent removal of the brick to clean the ladle of the chilled iron. The skull which forms gradually in the bottom of the ladle cannot be removed without removing the 45 whole lining of the ladle. This temporarily puts the ladle out of use, as well as involving a very considerable expense of labor and materials for relinquishing the same. Our invention seeks to avoid these losses and delays 50 and practically renders the ladle continuous in use, as the portion requiring relining is

only an inconsiderable fraction of the whole surface of the ladle.

Figs. I and II show our invention as practiced with the ladle supported on special 55 framework. Any suitable frame may be employed; but in the figures just referred to we have shown a frame consisting of four corner-posts 22, supporting two I-beams 33, upon which rests the ladle, as hereinafter described. 60 4 is a power-cylinder bolted to and supported upon two I-beams 55, which rest upon the sill 66. The upper end of the cylinder 4 is substantially secured to the cross-beams 77. 8 is the ram for said cylinder, which is located 65 so as to be in line with the center of the ladle. The ladle, as illustrated, consists of a metallic shell 10, a brick or equivalent lining 11, and an inner lining 12, of loam. A hole is made in the bottom of the shell, in which is 70 inserted a plug 13, provided with a flange 13a, extending around the hole. This metal plate is covered over with the brick or other lining in such a way as to secure against leakage, and the lining is so arranged that when the ram 75 or plunger is pushed up through the bottom of the ladle only that portion of the lining is removed that lies directly on top of the plug, which portion of lining covers so small an area that it can be speedily replaced, while 80 the plug 13 can be reused. 14 14 are trunnions on the ladle which are adapted to rest in bearings 15 15, secured to the I-beams 33. 16 16 are bearing elbows or lugs which rest upon bearing-blocks 17 17, also secured at 85 the top of the I-beams 33. 18 18 are the usual lifting-lugs on the ladle, and 19 19 are links pivoted to the upper edge of the I-beam 33 and provided with hooked ends adapted to drop over the upper edge of the ladle. 20 90 95 represents the strata of skull which has accumulated on the bottom of the ladle. In the actual working of ladles this skull varies in thickness from that here shown up to enough to almost fill the ladle.

The mode of working our apparatus is as follows: The ladle containing the skull is swung over by a crane and set down upon the framework, as indicated in the drawings. The links 19 19 are then swung over the edge 100 of the ladle. Power is applied through the cylinder 4, and the ram 8 pushes out plug 13

and the section of lining immediately above the same and then the whole mass of skull lying upon the bottom of the ladle, as is more clearly seen in Fig. II. After the loosened 5 skull has been dumped out of the ladle plug 13 can be reinserted in its hole, and the small piece of brick lining which has been disturbed can be quickly replaced above said plug and the ladle be ready for immediate use.

10 In Fig. III we have shown the same principle employed in removing the skull when the ladle is set upon a ladle-car. 21 is the ladle-car upon the track 22, which runs over a pit 23. Located in said pit 23 is a cylinder 4', 15 having ram 8'. The ladle is adjusted centrally over said ram 8', and the swinging links 24 24, pivoted in the walls 25 25 of the pit, are hooked into the lugs 26 26 of the ladle. Power is then applied to the ram 8' and 20 the skull dislodged, as before described.

Having described our invention, we claim—

1. The combination of a ladle having a metallic shell with an opening in its bottom; a plug in said opening and a lining of brick 25 above said plug; a frame upon which said ladle is supported; hooks attached to said frame and adapted to engage the ladle and an ejecting power-cylinder and ram in alignment with the hole in the bottom of the ladle.
- 30 2. The combination of a ladle having a metallic shell; a frame upon which said ladle is supported; means for holding said ladle against movement during the ejection of the skull; a hole in the bottom of the shell of 35 said ladle; a plug for said hole and a lining of brick above said plug and an ejecting

power-cylinder and ram in alignment with the hole in the bottom of the ladle.

3. The combination of a ladle having a metallic shell with an opening in its bottom; a 40 plug for said hole; a lining for the ladle covering said plug; trunnions for said ladle and bearing-lugs on said ladle.

4. The combination of a ladle having a metallic shell with an opening in its bottom; a 45 plug in said opening and a lining of brick above said plug; a frame upon which said ladle is supported; means for attaching said ladle to said frame and an ejecting power-cylinder and ram located beneath said ladle. 50

5. The combination of a railroad-track; a ladle-car; a ladle mounted thereon having a metallic shell with an opening in its bottom; a plug in said opening and a lining of brick 55 above said plug and an ejecting-cylinder and ram located between the rails.

6. The combination of a railroad-track; a ladle-car; a ladle mounted thereon having a metallic shell with an opening in its bottom; a 60 plug in said opening and a lining of brick above said plug; a pit located on the track and an ejecting-cylinder and ram in said pit.

7. A ladle composed of a metallic shell, an opening in its bottom, a plug in said opening and a lining covering said plug. 65

Signed at Pittsburg, Pennsylvania, this 24th day of March, 1900.

JOHN A. WALDBURGER.

WILLIAM J. SMITH.
